DESIGN FOR A NOVELTY PIN

Adolph Frankenthaler, New York, N. Y.

Application September 5, 1939, Serial No. 87,048

Term of patent 3½ years

To all whom it may concern:

Be it known that I, Adolph Frankenthaler, a citizen of the United States, residing at No. 50 West 72nd Street, New York city, county of New York, and State of New York, have invented a new, original, and ornamental Design for a Novelty Pin, of which the following is a specification, reference being had to the accompanying drawing, forming part thereof.

Fig. 1 is a front elevational view of a novelty pin, showing my new design;

Fig. 2 is a rear elevational view thereof; and
Fig. 3 is an edge view.

I claim:

The ornamental design for a novelty pin, substantially as shown.

ADOLPH FRANKENTHALER.
